United States Patent Office.

ANDREW JACKSON CONNER, OF LOUISVILLE, KENTUCKY.

Letters Patent No. 105,306, dated July 12, 1870.

IMPROVEMENT IN CISTERNS INFLUX-REGULATORS.

The Schedule referred to in these Letters Patent and making part of the same.

To all whom it may concern:

Be it known that I, ANDREW JACKSON CONNER, of Louisville, in the county of Jefferson and State of Kentucky, have invented a new and useful Improvement in Cistern-Regulator; and I do hereby declare that the following is a full, clear, and exact description thereof, which will enable others skilled in the art to make and use the same, reference being had to the accompanying drawing forming part of this specification.

This invention relates to a new and useful improvement in means for regulating the flow of water from the roofs of buildings to a cistern and reservoir, and consists in a shifting spout and in an arrangement for automatically operating and shifting it, whereby the direction of the water is changed, as will be herein-after more fully described.

The accompanying drawing represents vertical section of the arrangement.

Similar letters of reference indicate corresponding parts.

A is the receiving vessel, within which the shifting spout is placed.

B is the shifting spout. This spout receives the water from the pipe C.

D is a reservoir placed beneath the vessel A, in which there is a float, E, which is attached to the shifting spout by the chain F.

The float E, when unsupported by water in the reservoir, holds the shifting spout in the position seen in the drawing, or ready set for rain.

The water falls upon the spout B, and more or less of it passes off through the waste-pipe G, but a portion finds its way into the reservoir D, through the pipe H, which causes the float E to rise. This relieves the shifting spout of its weight, and when this

takes place the weight I on the other end of the shifting spout draws that end of the spout down, which changes the direction of the water, and causes it to run into the cistern J through the pipe K.

L is a pipe for conducting a small stream of water into the reservoir D, so as to keep the float E at the highest point or near the top of the reservoir.

M is a siphon by which water is conducted from the reservoir.

When the cistern J becomes full enough, the float N in the cistern rises and causes the rod O, to which it is attached, to strike the spout and tip it back to its former position.

P is a guide for the end of the float-rod O.

R is a partition in the vessel A, upon the top of which the shifter-spout B is pivoted, so that it is free to turn in either direction, according as it is governed by the rise of the water in the reservoir and cistern.

Having thus described my invention,

I claim as new and desire to secure by Letters Patent—

1. A vibrating double spout, B, arranged centrally beneath a water-inlet pipe, C, and on a vertical support, R, so as to admit of being tipped to throw the water on either side thereof, in the manner set forth.

2. Vibrating the double spout B by means of the float E, chain F, weight I, float N, and rod O, as set forth, so that the rise of water in cylinder D will enable weight I to turn the spout toward reservoir J, while the rise of the water in said reservoir will then cause rod O to hold up the spout so as to throw the water into the waste-pipe G, all as shown and described.

A. J. CONNER.
